UNITED STATES PATENT OFFICE.

HERMAN KERNGOOD, OF BALTIMORE, MARYLAND, ASSIGNOR TO THE PERFECT CLASP COMPANY OF BALTIMORE CITY, OF MARYLAND.

DESIGN FOR A HOOK FOR GARMENT-FASTENERS.

SPECIFICATION forming part of Design No. 23,258, dated May 8, 1894.

Application filed March 23, 1894. Serial No. 504,869. Term of patent 7 years.

To all whom it may concern:

Be it known that I, HERMAN KERNGOOD, a citizen of the United States, residing at the city of Baltimore, in the State of Maryland, have 5 invented a certain new and original Design for a Hook for Garment-Fasteners; and I do hereby declare the following to be a full, clear, and exact description of the invention, such as will enable others skilled in the art 10 to which it appertains to make and use the same.

In the accompanying drawings which form part of this specification—

Figure 1 represents a perspective of the hook 15 and Fig. 2 a like view of the hook inverted.

The following are the leading features of the design. The hook A comprises a plate *a* pro-

vided with side lugs or ears *b* and an ear lug or ear *c*; the outer end of each of which lugs is circular and in each lug are intersected bars *d* 20 with openings or spaces *e* between the bars, and the bill *f* of the hook is rounded at its end and bent back over but in a plane above the plate *a*.

What I claim is—

The design for a hook for a garment fastener substantially as herein shown.

In testimony whereof I affix my signature in presence of two witnesses.

HERMAN KERNGOOD.
